[57]

ABSTRACT

A bit attached to a tool string is used for drilling a hole from the ground surface into or through a subterranean deposit of granular ore. Within the tool string is a passage through which fluid flows to the bit while drilling. Valve means positioned within the passage are controllable from the ground surface for diverting the flow of fluid from the bit to an eductor located above the bit for mining operation. A nozzle in the tool string, located above the eductor, is controllable from the ground surface to discharge a jet stream of fluid radially outward from the tool string for breaking up the ore matrix. Then the eductor pumps a slurry mixture of fluid and granular ore through the tool string to the ground surface.

SUBTERRANEAN SLURRY MINING APPARATUS

BACKGROUND OF THE INVENTION

1. Field of the Invention

This invention relates to mining underground deposits of granular ore, such as phosphates, by deep-well hydraulic apparatus and more particularly to a combination well-drilling and mining tool for extracting granular ore from subterranean beds.

2. Description of the Prior Art

Known methods for deep-well mining of granular ore, such as phosphates, require pre-drilling a well and lining the side walls with mud or a casing. Then, a mining tool is inserted through the well casing for disintegrating ore therebelow by jetting water into the matrix. A slurry mix is formed and pumped upward through the mining tool to the ground surface. Such methods are expensive because of costs of lining the hole, assembling and disassembling the drill pipe string, and assembling and disassembling the mining tool.

U.S. Pat. No. 3,311,414 discloses a well drilled by a mining tool itself without predrilling. Such use of the mining tool is suitable only where no layer of limestone or cap rock covers the phosphate matrix. Normally, there is such a layer and the hole must be predrilled and mudded before insertion of the mining tool.

U.S. Pat. No. 3,155,177 shows apparatus for underreaming a well that can also be used to bore deeper in the well. Electric operated valves convert the apparatus from drilling operation to under-reaming operation.

U.S. Pat. No. 1,851,565 shows a mining apparatus that is inserted into a pre-drilled hole. A mining agent is projected from a nozzle to fluidize the substance mined and the accumulated mixture is lifted by an injector upward through the mining apparatus to the ground surface. No provision is made for drilling with the mining apparatus.

In order to drill from the ground surface through any stratum to reach a deposit of granular ore, it is desirable to use a rotary type drilling rig. Upon reaching the granular ore deposit, which can be hundreds of feet below the ground surface, it is desirable to jet a stream of fluid into the ore matrix to form a slurry mixture of ore and water. One problem encountered in developing a combination drilling and mining tool is the establishment of controls at the ground surface by which underground tool operation can be converted from drilling to mining.

SUMMARY OF THE INVENTION

The present invention provides a combination tool for drilling to subterranean deposits of granular ore and mining the deposits at a maximum speed and with a minimum amount of tool handling. Since the tool is driven by rotary drilling equipment, it can rapidly penetrate through any stratum to reach a granular ore deposit. It is unnecessary to line the well or pull the tool after drilling because the tool string functions both as a drilling string and a mining conduit. To convert from drilling to mining operation, the tool is controlled from the ground surface by increasing the quantity of fluid flow into the tool. Also, an inner casing is turned to index a distributor nozzle for directing a jet stream of fluid through a desired port in the tool outer casing to break up the granular ore matrix opposite therefrom. Should the sides of the well subside about the tool after drilling, it is unnecessary to rotate the tool outer casing

in one embodiment of the invention because the mining jet can be indexed independently of the outer casing.

The mining apparatus includes a bit attached to a tool string having an eductor therein located above the bit and a plurality of flow passages therethrough. Rotary drilling equipment drives the tool string and bit to a desired depth and a distributor nozzle within the tool string discharges a jet stream of fluid outward therefrom to break up a granular ore matrix thereabout. The tool string includes an outer casing and an inner casing which turns therein for indexing the distributor nozzle from a closed position between ports during drilling to open positions in alignment with ports in the outer casing for mining. The eductor has a nozzle, plugged during drilling operation, which is opened by increasing fluid flow down the tool causing pressure to build up below the nozzle. A valve seals a flow passage to the drill bit when the eductor nozzle opens, thereby diverting fluid flow to the nozzle for mining operation.

BRIEF DESCRIPTION OF THE DRAWING

FIG. 1 is a broken sectional view in elevation of apparatus embodying the present invention for drilling a well.

FIG. 2 is a broken sectional view in elevation of the apparatus shown in FIG. 1 used for mining.

FIG. 3 is an enlarged central vertical sectional view of the swivel sub assembly shown in FIG. 1.

FIG. 4 is an enlarged central vertical sectional view of the tool head assembly shown in FIG. 2.

FIG. 5 is a section taken on the line 5-5 of FIG. 4.

FIG. 6 is a broken longitudinal section of a typical tool section.

FIG. 7 is a view looking in the direction of arrows 7-7 in FIG. 6.

FIG. 8 is a view looking in the direction of arrows 8-8 in FIG. 6.

FIG. 9 is an enlarged central vertical section of the distributor shown in FIGS. 1 and 2.

FIG. 10 is a section taken on line 10-10 of FIG. 9.

FIG. 11 is a perspective view of the inner distributor with portions broken away to show underlying structure.

FIG. 12 is an enlarged central vertical section of the eductor nozzle and tool bit valve shown in FIGS. 1 and 2.

FIG. 13 is a perspective view of the eductor nozzle housing.

FIG. 14 is a section taken on line 14-14 of FIG. 9.

FIG. 15 is a section taken on line 15-15 of FIG. 14.

FIG. 16 is a diagrammatic view of a modified form of the invention shown in FIGS. 1-15.

FIG. 17 is an enlarged vertical section through the modified tool head assembly shown in FIG. 16.

FIG. 18 is an enlarged vertical section through the modified mining nozzle shown in FIG. 16.

FIG. 19 is an enlarged vertical section through the modified eductor nozzle plug and tool bit valve shown in FIG. 16.

FIG. 20 is a section taken on line 20-20 of FIG. 19.

DESCRIPTION OF THE PREFERRED EMBODIMENTS

With reference to FIG. 1, the mining apparatus includes a drill bit 20 attached to a tool string 21 that is driven by a portable rotary-type drilling rig 22. The drill bit can be any conventional type for a rotary drill

but preferably would have pivotable cutter arms 20a that collapse within the body of the bit when the tool string is lifted. A suitable bit is manufactured by Servco, P.O. Box 20212, Long Beach, California, and known as the Servco Model B Drilling-Type Hole Opener. The drilling rig has a mast 23 supported on a pair of skids 24 and 25. While skids have been shown, the drill mast could be supported on a barge or other movable mount for over-water operation or mounted on movable units such as wheeled or crawler type vehicles for land operation.

A platform 26 has ends slidably engageable with tracks 27 and 28 that extend vertically on mast 23. Mounted to the platform is a swivel 29 coupled by a hanger 30 to a cable 31 which raises or lowers the platform on the mast. A rotative portion of the swivel extends through an opening in the platform and a large sprocket 32 is keyed thereto beneath the platform. The sprocket is driven through a chain 33 by a motor 34 mounted on the platform. Since the platform and swivel for rotating the tool string can be elevated on the mast, it is possible to begin drilling a hole with the bit at ground surface without using a starting tool.

Tool string 21 is connected to the rotative portion of swivel 29 by a swivel sub-assembly 35 and drilling fluid is supplied by a hose 36 to a gooseneck 37 then through the swivel and swivel sub-assembly to the tool string. The swivel sub-assembly, shown in FIG. 3, has a stub end 40 adapted for coupling with the rotative portion of the swivel and a bell end 41 that couples with the tool string. Projecting outward from the bell end is a circumferential flange 42 having a guide skirt 43 bolted thereto that depends in parallel spaced relationship with the bell end. A passage 44 extends through the stub end to the bell end interior where a fitting 45 is located having a conical plug 46 and ports 47 to direct fluid flow from passage 44 into an annular passage 48 between the bell end and fitting. The lower end of the fitting fits telescopically into an inner tube socket of a dual pipe stand which will later be described and a packing 45a is provided thereabout. Below the conical plug is a passage 45b which enables a small quantity of drilling fluid to flow down and clean the interior of the inner tube during drilling.

Looking now at FIG. 2, a tool head 49 is shown mounted on tool string 21 for mining operation. The tool head has a T-section 50 with a mining fluid or water intake conduit 51 and a bracket 52 is mounted on the T-section for supporting a reducer drive motor 53. A swivel joint 54 connects the T-section with a coupling flange 55 having a large sprocket 56 mounted thereon. The reducer drive motor drives a small sprocket 57 and sprocket chain 58, trained about the large and small sprockets, turns the large sprocket and coupling flange. A swivel joint 59 mounted above the large sprocket is joined to a slurry discharge conduit 60.

As shown in FIG. 4, an inner pipe 62 fixed to coupling flange 55 extends through swivel joint 54 and T-section 50. A pipe coupling 63, attached to the lower end of the inner pipe, connects with an inner tube assembly of tool string 21 for sealing and transmitting torque therebetween. Within the inner pipe is a slurry density measuring line 64 coupled at the top with a passage 65 extending inward through the coupling flange and at the bottom with a fitting 66 extending from pipe coupling 63. A pipe nipple 67 connects the fitting with

a stab joint 68 that inserts into a socket end of line 68a (FIG. 6) extending downward between inner and outer tube assemblies of the tool string. Swivel joint 54 has an upper rotative portion 70 bolted to the coupling flange and coupled by ball bearings 71 to a lower stationary portion 72 bolted to T-section 50. A union fitting 73 is attached to conduit 51 of the T-section and a threaded pipe coupling 74 joins the lower end of the T-section with an outer tube assembly of the tool string.

Tool string 21 includes a series of tool sections 75, as shown in FIGS. 6, 7 and 8, that extend from swivel sub-assembly 35 (FIG. 1) or tool head 49 (FIG. 2) through a layer of overburden OB to a subterranean deposit of granular ore G.O. Each tool section has an outer tube 76 and an inner tube 77. A coupling 78, welded to the upper end of the outer tube, provides an internally threaded female connection 78a, while coupling 79, welded to the lower end thereof, provides a threaded male connection. Similarly, the inner tube has a female coupling 80 at the upper end and a male coupling 81 at the lower end, however, a key 82 projecting radially inward in the female coupling interlocks in an opening 83 (FIG. 6) in the male coupling reinforced by strap 83a so that adjacent inner tubes rotate together.

An external support flange 78b on coupling 78 is provided for supporting the tool sections 75 when not attached to adjacent sections. A support ring 84, held in concentric spaced relationship by arms 85 and 87 outside of female coupling 80, seats on a thrust bearing 84a within coupling 78 and lugs 86, projecting outward from male coupling 81, contact coupling 79 to maintain the lower end of the inner tube 77 in alignment within the outer tube 76 prior to engagement with an adjacent tool section. Line 68a, for measuring slurry density, fits through a support 87 located between the support ring and female coupling 80 and through an ear 88 projecting outward from male coupling 81.

The open annular cross-sectional area between the outer tube 76 and inner tube 77 is approximately the same as the open circular cross-sectional area within the inner tube. By approximately balancing these areas, the velocity of fluid flowing downward in the annular passage between the outer tube and inner tube is substantially the same as the velocity of fluid flowing upward within the inner tube. The head losses due to friction of fluid flowing in the tubes is minimized under this condition.

Inner tube 77 is the conduit through which a slurry mixture of granular ore is conveyed to the ground surface. By using the inner tube for the slurry passage, more clearance is provided for large modules of ore within the inner tube than would be available in the annular passage between the outer tube 78 and inner tube. Furthermore, the slurry mixture contacts only the inner tube, which can be replaced in the event of excessive wear.

Each tool section 75 is arranged for rapid coupling with an adjacent tool section by progressive engagement of inner tube couplings 80 and 81, key 82 and opening 83, lines 68a which are connected by stab joints, and outer tube couplings 78 and 79. O-ring seals are fitted about inner tube male coupling 81, line 68a at the stab joint, and outer tube male coupling 79 to provide fluid tight connection. Threads within outer tube female connection 78a and on the male connection of coupling 79 are tapered for fast engagement and disengagement.

As shown in FIGS. 1 and 2, tool string 21 includes a distributor 90, an eductor 91 and a bit valve 92 that are located between tool sections 75 and bit 20. The distributor has an outer body, as shown in FIG. 9, formed by an upper section 93 joined to lower section 94. An internally threaded socket 95 is provided at the top of upper section 93 to join with male coupling 79 of a tool section 75 and an internally threaded socket 96 is provided at the bottom of lower section 94 to join with an outer casing about the eductor. An upper ball race 97 and a lower ball race 98 extend circumferentially about the interior of lower section 94, which has eight radial ports 99 (FIG. 10) providing communication therethrough. The lower section interior surface adjacent the ports is lined with hardened wear resistant material 94a.

Distributor 90 has an inner body formed by a tube 103 with a female coupling 104 at the top and a male coupling 105 at the bottom. Within the female coupling is a key 106, similar to key 82, for locking within an opening 83 of a male coupling 81. A nozzle 107 having sets of straightening vanes 108 and 109 fitted therein extends transversely through the tube 103 which bulges thereabout perpendicular to the nozzle as shown in FIG. 10, to maintain a certain minimum cross-sectional clearance in the tube. A cylindrical shell 110, spaced from tube 103 by a top ring 111 and a bottom ring 112, rotatably fits within the interior of lower section 94 and has a lining 110a of hardened wear resistant material opposite material 94a. The rings 111 and 112 have ball races 113 and 114 positioned for alignment with ball races 97 and 98, respectively. Ball bearings 115 are fed through loading holes and fitted within the ball races enabling the cylindrical shell to turn freely within the lower section of the outer distributor body while held in place axially therein. Spaced circumferentially around top ring 111 are vertical ports 116 and around bottom ring 112 are vertical ports 117 which allow fluid to flow downwardly to eductor 91 and bit 20. A seal 119a is positioned above the top ring while a seal 119b is positioned below the bottom ring to prevent fluid reaching the ball races. Positioned between tube 103 and shell 110 behind nozzle 107 is a deflector 118 for directing fluid into the nozzle.

A line 120, which couples with line 68a of tool section 75, is attached to the outside of female coupling 104 and communicates with the interior of tube 103 for determining fluid pressure at that location to calculate slurry density. Also attached to the outside of the female coupling is an ear 121, shown in FIG. 14 having internally threaded openings therein to receive bolts 122 and 123 which hold in place a connecting plate 124. A rectangular slot 125 at the edge of the connecting plate adjacent upper section 93 is aligned over a recess 126 at the base of internally threaded socket 95. The recess is enclosed on the interior side by a plate 127 welded to the socket base and a shear key 128 fits within the slot and recess to lock tube 103 from rotation within the outer distributor body during drilling operation. In the locked position, nozzle 107 is positioned between ports 99 to prevent fluid discharge from the nozzle during drilling and to prevent foreign matter from plugging the nozzle. A multiplicity of recesses 126 are provided around the socket base enabling the nozzle to be locked between any two adjacent ports.

An outer casing 132, shown in FIG. 2, has a top portion that connects within internally threaded socket 96 (FIG. 9) of distributor 90, while the bottom portion is connected to an inlet housing 134 of eductor 91. The eductor includes a nozzle 145 within the inlet housing, a mixing chamber section 133 having a tapered entrance 133a connected to the inlet housing above the nozzle, and a diffuser tube 130 that extends from the mixing chamber section to a rotatable joint 131 joining male coupling 105.

Eductor inlet housing 134, shown in FIGS. 12 and 13, has a top ring 135 and a bottom ring 136 spaced between a pair of conduits 138 and 139 having vertical passages therein. These passages provide communication from the annular passage between outer casing 132 and mixing chamber section 133 to a chamber 137 below the bottom ring. Radial openings 140, located between each conduit on opposite sides of the outer casing, provide communication from outside the outer casing to an axial passage 141 that extends vertically above nozzle 145. These radial openings provide a large slurry intake adjacent the eductor nozzle to draw in a maximum quantity of ore for suction developed. The base of the conical shaped nozzle seats within an axial opening in the bottom ring and is held in place by an overlapping retainer ring 146 bolted to the bottom ring.

Chamber 137 is enclosed by a casing 142 welded to bottom ring 136 and externally threaded at the lower end for attachment within an internally threaded socket 143 at the top of a bit coupling 144. An axial passage 147 extends from the chamber through the bit coupling to a threaded socket 148 where bit 20 is attached. A valve seat 149 fits in the entrance to the axial passage for bit valve 92 to seat thereon and a valve cage 150 covering the bit valve within the chamber is bolted to the bit coupling. The bit valve has guide vanes 152 that extend downward into the axial passage and a flange 153 that seals the passage entrance when seated on the valve seat. A small passage 154 is provided in the bit valve enabling some fluid to reach the bit during mining operation for maintaining the material thereabout in a fluidized state until the bit is raised.

Bit valve 92 is attached to a guide tube 156 that slidably fits through valve cage 150 and has a sleeve bearing 157 within the upper end thereof. A stem 158 slidably fits telescopically through the sleeve bearing into the guide tube interior where an enlarged head 159 formed on the stem prevents withdrawal of the stem from the guide tube. The stem end opposite from the enlarged head fits through eductor nozzle 145 where a plug 160 is fitted thereacross and held in place by a shear pin 161. The stem and guide tube hold the plug in position blocking the eductor nozzle and a seal under the plug prevents leakage of drilling fluid while the tool bit valve is retained in an elevated position at the top of the valve cage. The plug also prevents foreign matter which might enter the eductor inlet housing 134 during drilling operations from obstructing the eductor nozzle.

In operation, drilling rig 22 is moved to a desired location and tool string 21, with bit 20 attached, is connected to swivel sub-assembly 35. Rotation of the drill string causes the bit to open a hole and tool sections 75 are added to the tool string until a desired depth is reached. During drilling operation, a drilling fluid such as water is fed through hose 36, gooseneck 37, swivel 29 and swivel sub-assembly 35 to an annular passage

between inner tube assembly 77 and outer tube assembly 76. The fluid flows downward through the tool string past bit valve 92 to the cutting heads of the bit and then upward between the outer surface of the tool string and sidewalls of the hole to the ground surface as indicated by the arrows in FIG. 1.

Upon reaching the desired depth, swivel sub-assembly 35 is disconnected from tool string 21 and tool head 49 is attached thereto. Water pumped into conduit 51 flows downwardly through the tool string between inner tube assembly 77 and outer tube assembly 76 to bit valve 92. As the flow is increased, pressure builds up within chamber 137 to a predetermined amount at which shear pin 161 breaks, opening eductor nozzle 145 and closing bit valve 92.

The downward flow in tool string 21 is then directed upward through eductor nozzle 145 and inlet housing 134 to mixing chamber section 131. The jet stream through the inlet housing creates a suction that draws granular ore inward through radial openings 140 therein. A slurry mixture of granular ore and water flows upward, as indicated by the arrows in FIG. 2, through diffuser tube 130, distributor 90, inner tube assemblies 77 and tool head 49 to conduit 60 from which it is discharged into a tank, not shown.

The slurry density can be calculated by directing a purging flow of water down lines 120, 68a and 64 to determine the pressure of the slurry mixture at a point above distributor nozzle 107. Then knowing the vertical distance from that point to tool head 49 and the internal cross sectional area of inner tube assembly 77, the density can be calculated.

Motor 53 can then be actuated to rotate sprocket 57 turning chain 58, sprocket 56 and inner pipe 62. Shear key 128 is broken by rotational force and nozzle 107 is aligned to discharge through one of the ports 99. A portion of the water flowing downward in tool string 21 is then diverted at deflector 118 into nozzle 107 to be discharged in a jet stream into a deposit of granular ore G.O. When a sufficient amount of granular ore has been mined from one section of the matrix, the nozzle can be indexed to the next port 99 and the procedure repeated until the nozzle moves through one or more complete circles. Then tool head 49 is removed and swivel sub-assembly 35 is connected for pulling the tool string. When a lifting pull is applied to the tool string, the pivotable cutter arms of the drill bit close enabling the bit to be withdrawn even though the side walls of the well have closed in about the tool string. Drilling rig 22 is moved to the next location and the procedure repeated.

Sometimes it is desirable to control the jet flow from nozzle 107 by means other than input into conduit 51. Such control can be achieved by motor 53 rotating inner pipe 62 through a drive to align the nozzle with a port 99. When the nozzle is aligned to register with the port, the jet flow discharge is at a maximum but when the nozzle is aligned between ports, there is no discharge. By positioning the nozzle in partial alignment with the port, the effective area of the port orifice is reduced and thus the flow discharge is limited. In this manner, the head of water in the well cavity about the tool can be controlled to keep distributor nozzle 107 above water for more effective jet action.

Another embodiment of the invention is illustrated in FIGS. 16-20. A drilling and mining apparatus 170, shown in FIG. 16, has been modified for converting

back and forth between drilling and mining operations. Such a tool can mine an upper ore strata, then drill to a lower ore strata which is subsequently mined without lifting the tool. Since the drilling and mining apparatus is in many ways similar to the apparatus shown in FIGS. 1-15, only those modified portions will now be described in detail and it will be understood that portions not described are similar to previously described portions.

- 10 Drilling and mining apparatus 170 includes a bit 171 attached to a tool string 172 upon which a tool head 173 is mounted. The tool head is fixed to a platform 174 by a mounting ring 175. A T-section 176 is bolted to the mounting ring and extends upward with a horizontal intake conduit 177 provided for drilling and mining fluids such as water. A slurry discharge conduit 178 extends vertically through the T-section and bends to a horizontal alignment at the discharge end.
- 15 A motor reducer 180 mounted to the side of T-section 176 drives shafting joined by a flexible coupling 181 and extending through bearing block 182 to turn a drive sprocket 183. The drive sprocket is connected by a sprocket chain 184 to a driven sprocket 185 mounted on a rotative portion of tool head 173 to which tool string 172 is attached.

With reference to FIG. 17, mounting ring 175 has a pair of ball races 187 and 188 spaced vertically along an interior face thereof. Fitting within the mounting ring is a casing 189 that has ball races on the outer face 30 to mate with ball races in the mounting ring. The casing is rotatively suspended by ball bearings inserted in place within the ball races and centered in alignment with the axis of T-section 176. Driven sprocket 185 is fixed to the casing below the mounting ring for rotating the casing and a threaded male coupling 190 is provided at the lowermost end of the casing for attachment to tool string 172.

Within casing 189, an inner ring 191 is aligned axially with slurry discharge conduit 178 and supported by 40 lugs 192 and 193 that project inward from the casing beneath a flange 194 on the inner pipe. A seal 195 is provided between the inner pipe and slurry discharge conduit to make the joint therebetween fluid tight. Spacer lugs 196 and 197 maintain the inner pipe in 45 axial alignment within the casing and a male coupling 198 at the lower end of the inner pipe fits telescopically within a female coupling 199 of an inner tube in tool string 172.

50 Hydraulic fluid is supplied to tool head 173 through a line 200 that threadably fits into T-section 176. A passage 201 extends within the T-section from line 200 to the joint between the T-section and casing 189. An annular passage 202 formed between seals 203 and 204 is continuously in flow communication with passage 201. A drain passage 205 is provided in the T-section to relieve excessive fluid that seeps between a seal 204a and seal 204.

55 A passage 206 extends from annular passage 202 through casing 189 and support lug 192 to a line 207 coupled with spacer lug 196. From line 207, a passage 208 extends through spacer lug 196 and inner pipe 191 to a conduit 209 that passes down the interior of male coupling 198 overlapping female coupling 199. An annular passage 210 formed between the male and female 60 couplings is connected by a port with conduit 209. Extending outward from the annular passage through the female coupling and a support lug 212 is a passage 211

to which a line 213 is connected for providing hydraulic fluid to the tool string 172.

Within tool string 172 is a mining nozzle 215, shown in FIGS. 16 and 18, that extends transversely through an inner tube 216 to the outer surface of an outer casing 217. This nozzle is fixed in position between the inner tube and outer casing and to orient the nozzle, it is necessary to rotate the tool string. A longitudinal passage 218 extends through the nozzle to an orifice 219 located at the discharge end thereof. Fluid flow from the nozzle is controlled by a valve stem 220 that slidably fits through ring guides 221a and 222b supported by straightening vanes 221 and 222 within the longitudinal passage. A seal 223 located at one end of the valve stem is adapted to block orifice 219 when positioned therein to prevent loss of fluid and avoid plugging of the nozzle by foreign matter during drilling operation.

Near the end of valve stem 220 opposite from seal 223 is a vertical slot 224 in which the end of lever arm 225 is slidably coupled. Thus, only horizontal force is transmitted to the valve stem, though the end of the lever arm moves through an arc. The opposite end of the lever arm is pivotably connected to an ear 227 fixed to inner tube 216. One end of a rod 228 is pivotably connected to an intermediate point of the lever arm, while a piston 229 fixed to the opposite rod end is slidably fitted within a hydraulic cylinder 230. A coil spring 231 fits around the rod between the piston and hydraulic cylinder end adjacent the lever arm to urge the rod in the direction opposite from the lever arm. Conversely, a passage 232 connects line 213 with the hydraulic cylinder and fluid pressure urges the piston in the opposite direction. It will be seen that the valve stem is resiliently held in a position blocking orifice 219 until hydraulic pressure applied to the piston forces the lever arm and valve stem rearward opening the orifice.

With reference to FIGS. 16, 19 and 20, an eductor 235 located within tool string 172 below mining nozzle 215, is similar to previously described eductor 91. However, hydraulic operated valve means control fluid flow to an eductor nozzle 236 and to bit 171. A single acting hydraulic cylinder 237 is bolted to a bottom ring 238 which supports the nozzle. A double end rod 239 extends through the hydraulic cylinder and a piston 240 is mounted intermediately thereon within the hydraulic cylinder. Fitted around the rod between the piston and a lower end 241 of the hydraulic cylinder is a coil spring 242 which urges the piston upward. A seal 243 is provided at the upper end of the rod to block nozzle orifice 244 when the spring forces the piston to a top end 245 of the hydraulic cylinder. A valve 246, mounted at the lower end of the rod, seats within axial passage inlet 247 leading to the bit when the piston is forced downward to the position shown in FIG. 19. Hydraulic pressure is transmitted to the top side of the piston through a passage 248 to the top end 245 of the hydraulic cylinder which is connected to line 213.

Operation of the embodiment of the invention illustrated in FIGS. 16-20 differs from that of the previously described embodiment as follows: During drilling, no hydraulic pressure is applied to line 200 in tool head 173 so nozzle orifices 219 and 244 are blocked, while axial passage inlet 247 is open allowing fluid to flow to bit 171. Upon reaching a desired depth for mining, hydraulic pressure is applied to line 200 and is transmitted through line 213 causing nozzle orifices

219 and 244 to be opened and valve 246 to be closed. Drilling fluid flows downward, as indicated by solid line arrows 250 in FIG. 19, and upward through eductor nozzle 236. Flow through the nozzle creates a suction that draws in slurry, as represented by dotted line arrows 251, which flows upward through eductor 235. The mining operation is conventional but to rotate mining nozzle 215, the entire tool string 172 is rotated by driven sprocket 185 in the same manner as when drilling. After mining one ore strata, it may be desirable to drill down further and mine a lower strata. This can be accomplished by reducing the fluid pressure applied to line 200, allowing nozzle orifices 219 and 244 to be blocked while valve 246 is opened, and proceeding with drilling until the second ore strata is reached. Then fluid pressure is applied to line 200 and mining operation is resumed.

Although the best mode contemplated for carrying out the present invention has been herein shown and described, it will be apparent that modification and variation may be made without departing from what is regarded to be the subject matter of the invention.

What we claim is:

1. Apparatus for mining a subterranean deposit of granular ore comprising a bit, and a tool string attached to the bit for drilling a hole from the ground surface through a layer of overburden into said granular ore deposit; said tool string having a passage therein through which fluid flows to said bit during drilling operation, an eductor located in the tool string above said bit, hydraulic operated valve means located in said passage for closing off fluid flow to said bit and allowing fluid flow to said eductor for mining operation, and a slurry passage centrally situated within said tool string through which fluid and granular ore are conveyed from the eductor to the ground surface during mining operation.

2. The apparatus described in claim 1 including means for directing some fluid downward through the slurry passage during drilling operation to keep the passage clean.

3. The apparatus described in claim 1, wherein said bit has movable cutters extendable by applying torsional forces such that said bit opens a hole larger than the outside diameter of the tool string but retracts to less than the tool string diameter for withdrawal from the hole when the torsional forces are relieved.

4. The apparatus described in claim 1 including a nozzle located within the tool string above the eductor for directing a jet stream of fluid outward from the tool string during mining operation to break up a granular ore matrix thereabout and means for modulating the flow of fluid from said nozzle independent of the quantity of fluid supplied to said tool string passage.

5. The apparatus defined in claim 1 wherein said hydraulic operated valve means, held in place by a deformable member, are actuated by deformation of the member in response to a predetermined fluid pressure developed by increasing fluid flow down the tool string passage towards the bit.

6. The apparatus defined in claim 5 wherein said eductor includes a nozzle and said hydraulic operated valve means for diverting fluid flow from said bit to said eductor includes a plug fitted across said eductor nozzle, a valve fitted within said fluid flow passage to said bit, and means interconnecting said plug and valve to maintain the nozzle plugged and the valve open until

said predetermined pressure is reached whereupon said interconnecting means separate to open the nozzle and seat the valve.

7. The apparatus defined in claim 6 wherein said valve has a passage therein through which a small amount of fluid can flow to the bit during mining operation to maintain the material about the bit in a fluidized state until the bit is lifted.

8. The apparatus defined in claim 6 wherein said plug and valve interconnecting means include a valve cage fitted across the fluid flow passage to the bit for retaining the valve therein, a guide tube connected to the valve and slidably fitted through the valve cage, a stem linked to the guide tube, and a shear pin fastening the plug to the stem whereby said valve is retained in an open position within the valve cage and said plug is held over the nozzle.

9. Subterranean mining apparatus as described in claim 1, including a nozzle located within said tool string above the eductor for directing a jet stream of fluid outward from the tool string to break up a granular ore matrix thereabout, and means for sensing pressure of the mixture of fluid and granular ore in the slurry passage near the nozzle.

10. The apparatus described in claim 9 wherein said nozzle is rotatably mounted with rotating means such that it can be moved in a horizontal plane without rotating said tool string and bit.

11. The apparatus described in claim 1 including means for actuating said hydraulic operated valve means independent of the fluid pressure in the tool string passage below the eductor.

12. The apparatus described in claim 11 wherein said eductor has a nozzle and said hydraulic operated valve means includes a hydraulic cylinder with a double end rod, a valve attached to one end of the rod and adapted to seat within the fluid flow passage to the bit, and a plug attached to the outer end of the rod and adapted to block a passage in the eductor nozzle, said hydraulic cylinder being operable to move the double end rod alternately opening the valve and plugging the nozzle or seating the valve and withdrawing the nozzle plug.

13. The apparatus described in claim 1 including a

nozzle located within the tool string above the eductor for directing a jet stream of fluid outward from the tool string during mining operation to break up a granular ore matrix thereabout and means for blocking the nozzle during drilling operation to prevent discharging fluid therefrom and plugging of the nozzle with extraneous matter.

14. The apparatus described in claim 13 wherein said nozzle has a longitudinal passage extending transversely of the tool string to an orifice at the discharge end of the nozzle, a valve stem slidably fitted for longitudinal movement within the longitudinal passage and adapted to block the orifice when positioned therein, and control means for slidably moving said valve stem between positions opening and blocking the orifice.

15. The apparatus described in claim 14 wherein said control means include hydraulic controls that regulate the hydraulic operated valve means simultaneously for drilling or mining operations.

16. In subterranean mining apparatus, a tool string having an inner tube assembly and an outer tube assembly, said outer tube assembly having a plurality of radial ports spaced circumferentially thereabout at one level, said inner tube having a nozzle therein at the level of said radial ports for directing a jet stream of fluid therethrough, and means for rotating said inner tube assembly relative to said outer tube assembly and thereby indexing said nozzle with said radial ports.

17. In subterranean mining apparatus as described in claim 16, means for locking said inner tube assembly with said outer tube assembly when the nozzle is positioned between two radial ports, said locking means being shearable by rotative force applied by said rotating means to index said nozzle with said radial ports.

18. The apparatus described in claim 16 wherein said nozzle is positioned in partial alignment with a port to reduce the fluid flow therethrough.

19. The apparatus described in claim 16 including ball bearings positioned between said inner and outer tube assemblies to hold the nozzle at the level of the radial ports and to reduce rotational friction between the inner and outer tube assemblies.

UNITED STATES PATENT OFFICE
CERTIFICATE OF CORRECTION

Patent No. 3,747,696 Dated July 24, 1973

Inventor(s) William Z. Wenneborg, et al.

It is certified that error appears in the above-identified patent and that said Letters Patent are hereby corrected as shown below:

Column 8, line 38, "ring" should read --pipe--.

Column 11, line 38, "outer" should read --other--.

Signed and sealed this 24th day of June 1975.
